UNITED STATES PATENT OFFICE.

DONALD J. CAMPBELL, OF MUSKEGON HEIGHTS, MICHIGAN.

MECHANICAL SAND-RAMMING MACHINE.

1,321,283.

Specification of Letters Patent. Patented Nov. 11, 1919.

Application filed June 14, 1919. Serial No. 304,328.

To all whom it may concern:

Be it known that I, DONALD J. CAMPBELL, a citizen of the United States of America, residing at Muskegon Heights, in the county 5 of Muskegon and State of Michigan, have invented certain new and useful Improvements in Mechanical Sand - Ramming Machines; and I do hereby declare the following to be a full, clear, and exact description 10 of the invention, such as will enable others skilled in the art to which it appertains to make and use the same.

This invention relates to sand ramming machines for use in ramming sand mechanically in a flask around a mold. It is essential in molding that the sand be rammed so as to have a certain solidity about a mold and usually it is done manually, the operator tamping or ramming the sand with a 15 suitable implement for the purpose. In my invention it is designed that the sand shall be delivered into the flask and at the same time put into the flask with force sufficient to practically ram the sand to the required 20 degree, all being accomplished mechanically and without the intervention of labor other than the operator of the machine. A further object of the invention is to provide a machine in which a considerable range of 25 movement is present so that the sand may be directed to different parts of the flask as necessary for the proper filling of the flask. Other objects and purposes consist of means 30 for bringing the sand to the machine in proper relation thereto to be received and acted upon by it, in means for controlling the passage of sand to the machine, in novel constructions and arrangements of parts for automatically insuring that the machine 35 shall deliver the sand to the mold, and in many other novel features of construction for the effective accomplishment of the ends for which the invention is designed, all of 40 which will appear fully and in detail as 45 understanding of the invention is had from the following description, taken in connection with the accompanying drawings showing a preferred form of the invention, in which drawings,

50 Figure 1 is a side elevation of the sand conveying means for bringing the sand to the mechanical ramming mechanism.

Fig. 2 is a partial vertical section and elevation of the mechanical sand ramming device, its mounting and operating mechanism 55 for driving the same.

Fig. 3 is a vertical section taken transversely through the sand ramming mechanism, the motor for driving the same and the outlet thereto, and

60

Fig. 4 is a front elevation thereof.

Like reference characters refer to like parts in the different views of the drawings.

In construction, a support comprised of vertical posts 1, attached to a suitable base 2 and with diagonal braces 3 disposed between a sand receiving receptacle 4 on the base 2 and upper framework 5 at the upper ends of the posts 1 is provided, there being horizontal cross brace members 6 and 7 between the posts and the diagonal brace 3 for strengthening the support. The base may be of any suitable size to make a suitable foundation which will not tip or be otherwise unsteady. An adjustable bearing 8 is mounted on the sand receptacle 4 and a fixed bearing 9 above the part 5 in which bearings 70 shafts 10 and 11 are mounted for rotation. An endless chain conveyer 12 with a succession of buckets 13 thereon passes around 75 wheels on the shafts 10 and 11. A motor 14 may be used to drive the upper shaft 11, any suitable form of driving connection being used and it is apparent that with the motor running the conveyer may carry sand 80 placed in the hopper 4a of the sand receptacle 4 upwardly and deliver it into a hopper 15 located in front of motor 14. A shaft 16 is mounted horizontally through hopper 15 and has a bell crank fixed at one end, one 85 arm of which is weighted, as indicated at 90 17 and to the other arm 18 a rope or cable 19 is attached the same leading over suitable guide pulleys 20 and 21, as shown and to the lower end of which a rod 22 is connected, its free end terminating in a handle 23. Operation of shaft 16 is designed to 95 control the delivery of the same so that the sand delivered to the hopper 15 may return to the lower sand receptacle 4 through the conduit 24 or be delivered to the chute 25 located directly below the hopper 15.

Said chute 25 is pivotally mounted at the upper end of a vertical rod 26 which is mounted to turn about a vertical axis 100 in bearings formed in upper and lower brackets 27 and 28 attached to and extending in front of the posts 1. The lower end of the rod 26 is sustained by a suitable thrust bearing carried by the lower bracket. 105 An extension pipe 29 is slidably mounted on the lower end of chute 25 and may be ex-

tended or retracted for different conditions of working. A tubular rod 30 is pivotally connected to the lower end of the pipe 29 at its upper end and between its ends has a 5 pivotal connection at 31 to the hopper of the mechanical sand ramming mechanism later described. A rod 32 telescopes within the lower end of the tubular rod 30 and may be adjusted to different positions and held 10 therein by a set screw, and the lower end of rod 32 is formed with an eye through which the rod 22 passes.

On the vertical rod 26 a supporting structure is mounted for vertical movements 15 lengthwise of the rod and for swinging movements about the rod. This structure comprises an upper horizontally located open frame 33, a lower block 34 and diagonally positioned braces 35 which in effect 20 makes a rigid and strong bracket support for carrying the sand ramming device. A screw 36 passes upwardly through the block 34, having threaded connection therewith and its lower end passes into a member 37 25 located below the block and fixed to rod 26. A spiral gear 38 is attached to the screw within member 37 meshing with which is a second spiral gear 39 fixed to a horizontal shaft which has a squared end 40 adapted to 30 receive a crank for operating the screw to raise or lower the bracket supporting structure. This supporting structure turns with the rod about its vertical axis and it is apparent that a considerable range of movement therefor is provided.

A cylindrical track 41 is attached to and 35 extends horizontally in front of the supporting structure. At its outer end a stop block 42 is fixed for use to limit the travel of 40 a carriage mounted to move back and forth over the track. As shown in Figs. 3 and 4, the carriage comprises spaced apart brackets 43 between which rollers 44 are rotatably mounted to ride on track 41, a plate 45 connecting the brackets at their upper ends 45 making a structure on which an electric motor 46 may be placed. Below the carriage the casing 47 of the sand ramming mechanism is placed and it is suspended from the 50 carriage, having a lug 48 at its upper side passing between the brackets 43, suitable connections being made between the brackets and lug. In Fig. 2 a slight modification is indicated, the motor resting directly on plate 55 45 from which suitable mountings for the rollers 44 depend, the casing 47 being suspended from the motor shaft through depending side members 43a. The casing has a hopper 49 at one side into which the sand 60 goes through chute 25 and extension 29 thereof and thence into the casing and at an opposite side is provided with an outlet 50.

A shaft 51 passes centrally through the casing 47 and is mounted for rotation. 65 Within the casing and attached to the shaft

51 a sand wheel 52 is located which is formed at its outside and at opposite sides with lips 53 extending entirely around the wheel, there being a cross member 54 a distance within the outer edges of the wheel 70 and a series of spaced apart division partitions which make a series of pockets at the periphery of the wheel adapted to receive sand. The bottoms of the pockets are made partly by the cross members 54 and completed by the sides 56 of a plurality of members, one for each pocket, which are pivotally mounted on a series of short cross shafts 57 carried by and within the sand wheel. From each of said members an arm 80 58 extends inwardly, passing alongside of a cam 59 fixed to one side of the casing 47 as best shown in Fig. 3. A cam groove 60 is cut in the inner side of the cam 59 and each arm 58 has a roller 61 at its end entered into and adapted to traverse the groove when the sand wheel is rotated. The cam slot is so shaped that with the rotation of the wheel 52, as each pocket approaches the outlet at 50, the side 56 is moved about its 90 pivot so as to force the sand from the pocket and into the outlet 50. It is apparent that with the wheel rotating to the right (referring to Fig. 2), as each pocket comes to the outlet at 50 a certain amount of sand is practically scooped into the pocket and rests against the movable part 56 of the bottom of the pocket, so that when this movable part is moved outward the sand is forced to go from the pocket and does not continue 100 with the wheel.

A nozzle 62 is mounted at the end of the outlet 50 and may be turned at different angles with respect thereto, a universal joint connection, such as illustrated at 63 105 being used between the nozzle and outlet. A handle 64 is attached to a side of the nozzle and with it the nozzle may be turned by the operator to direct the sand coming out of the nozzle to different parts of the 110 flask 65 located below the lower end of the nozzle.

A pulley 66 is fixed on the motor shaft 46a and a similar pulley 67 on the shaft 51 and a belt 68 passes around such pulleys for the 115 driving of the sand wheel by the motor. It is apparent that the sand wheel is driven at a high rate of speed by the motor and that each pocket receives a small amount of sand as it passes the hopper, the same bearing 120 against the movable section 56 of the bottom of the pocket and that it is thrown from the wheel with considerable force when the section 56 is moved outward at the upper end of the outlet 50. This causes 125 the sand to be delivered in a consecutive series of jets, one following quickly after the other and passing from the nozzle 62 into the flask. The force of ejection of the jets of sand makes the same collect in a 130

compact mass in the flask and around the pattern therein so that the sand mold is as compact and fully rammed as need be.

It will be noted that the nozzle may be turned to any position, that the carriage may be drawn back and forth on the track 41 for different widths of flasks, that the support for the carriage may be turned back and forth about the axis of rod 26 for different lengths of flasks and to reach different parts of a long flask, and that the support for the carriage may be raised or lowered for different heights of flasks as well, the machine being practically universal in its use for different sizes of flasks within reasonable limits. The extension pipe to the chute 25 is automatically extended and retracted with the outward and inward movements of the carriage as well as with the lowering and raising of the support therefor. The hopper 49 is always in position to receive sand delivered from the lower end of pipe 29. Any excess of sand coming to the hopper 15 may be returned when it is not needed by an easy operation always readily performed by the operator of the machine. Elevating and delivering of the sand to the flask and the ramming thereof is entirely performed by the machine, no shoveling or hand ramming being necessary. It is also apparent that the mechanism may be swung from side to side about the horizontal axis of the track rod 41. The device has all movements necessary to make a fully complete and operative working structure for accomplishing the ends sought.

While I have shown and described a complete and specific construction of the invention, it is realized that many changes in design may be resorted to without departing from the invention, and I, accordingly, do not limit my invention to the specific form shown and described but consider myself entitled to all forms and modifications of the invention which come within the scope of the appended claims defining the invention.

I claim:

50 1. In combination, a casing, sand inlet and outlet members at opposite sides of the casing, a sand wheel rotatably mounted within the casing, said wheel having a plurality of pockets at its outer portions to receive sand at the inlet to the casing and carry it to the outlet, each of said pockets including a movable bottom section, means to operate said movable bottom section to force the sand from each pocket as it approaches the outlet, and means to drive the sand wheel, substantially as described.

2. In combination, an inclosing casing of substantially cylindrical form provided with a sand receiving hopper at one side and an outlet member at the opposite side, a

sand wheel rotatably mounted within the casing and adapted to receive small quantities of sand from the hopper and eject them through the outlet member, means for driving the sand wheel and means for positively ejecting the sand from said pockets and through said outlet member, substantially as described.

3. In combination, a hollow cylindrical casing having a sand receiving hopper at one side and an outlet member at the opposite side, a shaft passing through the casing, a sand wheel on the shaft, said wheel having a plurality of pockets for receiving sand from the hopper located around the wheel, a movable bottom section for each pocket, means to turn the shaft, and means for moving the bottom section of each pocket outwardly as the pockets approach and pass by the end of the outlet member, substantially as described.

4. In combination, a hollow cylindrical casing having a sand receiving hopper at one side and an outlet member at the opposite side, a shaft passing through the casing, a sand wheel on the shaft, said wheel having a plurality of pockets around the same adapted to receive sand from the hopper, a movable bottom section to each pocket pivotally mounted on the sand wheel, a cam fixed to the casing, means to turn the shaft and attached wheel, and an arm for each movable bottom section engaging with the cam for forcing said bottom section outward as it approaches and passes by the end of the outlet member to the casing, substantially as described.

5. In combination, a support, including a horizontal track, a carriage mounted to move back and forth thereon, a casing suspended from the carriage and provided with a sand hopper at one side and an outlet member at the other, means rotatably mounted within the casing for taking sand in small amounts from the hopper and ejecting it through the outlet member, a motor mounted on the carriage above the casing, and means to drive said rotatably mounted means within the casing from the motor, substantially as described.

6. In combination, a casing provided with a sand receiving hopper at one side and an outlet member at the opposite side, a sand wheel rotatably mounted within the casing and adapted to take small quantities of sand from the hopper and eject them through the outlet member, means for driving the sand wheel, and a nozzle attached to the end of the outlet member and connected so as to have universal angular movement with respect thereto, substantially as described.

7. In combination, a supporting frame including fixed vertical members, a vertical rod mounted on and in front of said members for rotation about a vertical axis, a

70

80

90

100

110

115

120

125

130

bracket support mounted on the rod, means to raise or lower the bracket support, a horizontal track extending forward from the said bracket support, a carriage mounted to 5 move back and forth on the track, a casing suspended from the carriage, a sand wheel rotatably mounted within the casing, a sand hopper at one side of the casing, an outlet member at the opposite side thereof, a chute 10 pivotally mounted at the upper end of the vertical rod and adapted to empty into the hopper, means to carry sand to the chute, a motor carried by the carriage, and means to drive the sand wheel from the motor, said 15 sand wheel operating to receive small quantities of sand in succession from the hopper and eject them through the outlet member, substantially as described.

8. In combination, a support, a vertical 20 rod mounted on the support to turn about a vertical axis, a bracket support mounted on the rod, means to raise or lower the same, a horizontal track member extending from the bracket support, a carriage mounted thereon 25 to traverse the track member, a sand receiving and ejecting mechanism suspended from and movable with the carriage, a motor on the carriage for driving said mechanism, a hopper for receiving sand to supply the said 30 mechanism, said hopper having an open upper side, a chute pivotally connected to the upper end of the vertical rod, an extension length thereto at its lower end adapted to telescope thereon, and means to automatically move said extension with the 35 movements of the hopper so that the lower end of the extension is always located directly above the open upper side of the hopper; substantially as described.

40 9. In combination, a support, a vertical rod mounted on the support to turn about a vertical axis, a bracket support mounted on the rod, means to raise or lower the same, a horizontal track member extending from the 45 bracket support, a carriage mounted thereon to traverse the track member, a sand receiving and ejecting mechanism suspended from and movable with the carriage, a motor on the carriage for driving the mechanism, a 50 hopper movable with the mechanism for receiving sand to supply the said mechanism, said hopper having an open upper side, a chute pivotally connected to the upper end of the vertical rod, an extension length thereto at its lower end adapted to telescope 55 thereon, a rod pivotally connected at its upper end to the lower end of said extension and also pivotally connected to the hopper, and means to carry sand to the chute, substantially as described.

60 10. In combination, a sand receiving and ejecting mechanism, supporting means therefor including means for raising or lowering the mechanism, means for turning the same back and forth about a vertical axis, means

for swinging the same about a horizontal axis, and means for moving the same back and forth horizontally, substantially as described.

11. In combination, a sand receiving and 70 ejecting mechanism and supporting means therefor, including means for raising and lowering the mechanism, means for turning the same about a vertical axis positioned a distance back of the mechanism, means for 75 swinging the mechanism back and forth about a horizontal axis located a distance above the mechanism, and means for moving the mechanism back and forth parallel to the length of said horizontal axis, substantially 80 as described.

12. In combination, a sand receiving and ejecting mechanism and supporting means therefor, including means for raising and lowering the mechanism, means for turning 85 the same about a vertical axis located a distance back of the mechanism, means for swinging the mechanism back and forth about a horizontal axis located a distance above the mechanism, and means for moving 90 the mechanism back and forth parallel to the length of said horizontal axis, said mechanism having an outlet thereto and a nozzle attached to the outlet and connected movably thereto so as to swing to any desired 95 angle with respect to the outlet, substantially as described.

13. In combination, a support, sand conveying mechanism mounted thereon adapted to elevate sand from a lower position to the 100 upper portion of the support, means to drive the conveying mechanism, a hopper into which the sand is delivered, a conduit leading from the hopper back to the lower end of the conveying mechanism, a chute located 105 below the hopper and in front of the conduit, manually operable means for delivering the sand carried to the hopper either to the conduit or to the chute, and a mechanical sand receiving and ejecting mechanism located below the chute to which the chute 110 delivers the sand passing therethrough, substantially as described.

14. In combination, a support including a horizontal track, a carriage mounted to 115 move back and forth on the track, a cylindrical casing suspended from the carriage and provided with a sand receiving hopper at one side and an outlet member at the opposite side, a shaft extending through the 120 casing, a sand wheel on the shaft, said wheel being provided with a plurality of sand receiving pockets around the same having open sides coming to the hopper and the outlet member alternately, a movable bottom 125 section to each pocket, a cam fixed to one side of the casing, means interposed between the cam and each of said movable sections for moving the sections outwardly as the same approach and pass the end of the out- 130

let member, a motor carried by the carriage, and means to drive the shaft and attached wheel by the motor, substantially as described.

5 15. In combination, means to receive small quantities of sand in quick succession from a quantity of sand and eject the same with force into a molding flask, and means for carrying and delivering sand to said first 10 means, substantially as described.

16. In combination, means to receive small quantities of sand in quick succession from a quantity of sand and eject the same with force into a molding flask, and means for

directing the sand ejected to any desired 15 portion of the flask, substantially as described.

17. In combination, means to receive small quantities of sand in quick succession from a quantity of sand and eject the same with 20 force into a molding flask, a support for said means, and means for adjusting the said means to any one of a large number of positions for different lengths, widths, and heights of flasks, substantially as described. 25

In testimony whereof I affix my signature.

DONALD J. CAMPBELL.
